F. C. HERSEE,

TIMER.

APPLICATION FILED DEC. 7, 1915. RENEWED MAR. 17, 1920.

1,338,015.

Patented Apr. 27, 1920.

INVENTOR:

Frederick C. Hersee

By Clyde L. Rogers,

Atty.

UNITED STATES PATENT OFFICE.

FREDERICK C. HERSEE, OF BOSTON, MASSACHUSETTS.

TIMER.

1,338,015.

Specification of Letters Patent. Patented Apr. 27, 1920.

Application filed December 7, 1915, Serial No. 65,604. Renewed March 17, 1920. Serial No. 366,674.

To all whom it may concern:

Be it known that I, FREDERICK C. HERSEE, a citizen of the United States, and resident of Boston, county of Suffolk, Commonwealth of Massachusetts, have invented an Improvement in Timers, of which the following description, in connection with the accompanying drawings, is a specification, like characters on the drawings representing

10 like parts in each of the several views.

This invention relates to timers for internal combustion engines of the type wherein a rotating contact comes into wiping engagement with a series of relatively fixed 15 contacts spaced around the orbit of its path of movement and controlling the ignition in the respective cylinders. A prime object of the invention is to provide a timer of this character having the series of fixed contacts

20 variably spaced with reference to the path of movement of the movable contact member whereby different portions of said contact member are engaged by the different ones of the several fixed contacts, and pref-

25 erably in combination therewith an improved form of movable contact member that is automatically shiftable by wiping engagement with the fixed contacts so as to present a fresh contacting surface at each 30 engagement with the several fixed contacts, along with sufficient friction action against the coöperating contact to make the electrical connection reliable. To this end I pref-

35 erably form the movable contact member as a somewhat elongated roller mounted to re- 30-volve on a shaft and successively engaging a series of fixed contacts mounted so as to engage said roller at different points along the length thereof. A further object is to

40 provide an improved construction of timer wherein the external connections for all of the fixed contacts are located on the upper segment of the shell or housing so as to be conveniently reached. A further object is to

45 provide a construction wherein the movable contact element is of a simple inexpensive form that may be easily removed and replaced or renewed. A further object is to provide a timer shell or housing, bearing

50 relatively fixed contacts and a movable contact element to coöperate therewith, with provision for centering said shell, and the contacts carried thereby with reference to the rotatable contact when said movable

55 contact is applied to a driving shaft pre-

fixed in place. A further object is to provide an improved form of handle member for shifting the timer shell wherein said member is internally reinforced so that it may be constructed of fiber without danger 60 of breakage. A still further object is to provide an exceedingly simple construction of timer that is cheap to construct and adapted to have its movable element fitted by a simple connection to an operating shaft which 65 may be the cam shaft of the standard Ford type of automobile. The foregoing and other objects and features of the invention will be better understood from the following detailed description taken in connection with the accompanying drawings and will be thereafter pointed out in the appended 70 claims.

Referring to the drawings:

Figure 1 shows in side elevation a timer 75 constructed in accordance with my invention;

Fig. 2 is an end elevation thereof;

Fig. 3 is a lengthwise vertical section; and

Fig. 4 is a rear elevation of the timer shell with a portion thereof in section and with the rotatable contact and shaft removed.

The timer shell which may be molded of fiber or other suitable material is indicated 85 at 10 with a short cylindrical portion merging into a conical portion 11 and terminating in a reduced cylindrical cap portion 12. This shell is provided with an upstanding handle projection 13 which may be formed integral therewith and provided with a passage 14 to receive a pin or bolt for connection to an operating rod for shifting the timer shell angularly to advance or retard the spark. In accordance with one feature 95 of my invention this handle portion is reinforced by embedding therein a metallic strap member 15, the end portions of which extend inward with the extremities 16 bent laterally, while the intermediate portion is 100 bent to circular form as indicated at 17 to constitute a bearing and wear member for the passage 14. The fixed contacts are illustratively shown as four in number, each consisting in a ball 18 held at the inner end of a short metallic tube 19 which is externally threaded and fitted radially through the shell, the inner extremity of this tube being inturned to provide a proper holding seat 105 for the ball 18 while permitting said ball to 110

project therefrom. The several balls 18 are yieldingly pressed inward by a headed follower 20 pressed by a coil spring 21 housed in the tube 19 and reacting against the end 5 of a cap 22 threaded on the outer portion of the tube 19 and adapted to be set up against a metallic lock washer 23 threaded on the tube and adapted to be set up against the shell. For receiving the external electrical connections the caps 22 of the two upper contacts are equipped with outwardly projecting threaded stems 24 to constitute binding posts. In accordance with my invention, means is provided whereby the external 10 connections or binding posts of the two lower contacts are also located on the upper portion of the timer. For this purpose metallic strap connections 25 are provided having eyes 26 at their lower ends engaging 15 around the tubes 19 and other eyes 27 at their upper ends engaging around binding posts 28 fitted in the upper half portion of the shell adjacent the upper pair of contacts and equipped with lock nuts 29. Preferably and as shown these strap connections 25 are embedded in the fiber of the shell and do not project therefrom so as to be exposed at any point. Thus all of the contact 20 connections may be made from the upper half of the timer and the binding posts reached much more conveniently for making the connections.

The operating shaft, which may be the cam shaft of the standard Ford type of automobile is indicated at 30, with a reduced end portion 31 on which is fitted a sleeve 32 formed with a radial arm having bearings 33 in which are mounted a somewhat elongated roller 34, the axis of which is 35 parallel to the shaft 30. For securing the sleeve 32 to the shaft 30 a cotter pin 35 may be fitted in a radial bore of the shaft 30 with a bent portion 36 thereof extending 40 along a key way 37 in the sleeve 32. In accordance with my invention the several 45 fixed contacts 18 are mounted on the timer shell so as to be in spaced apart relation endwise of the roller 34, i. e., so that each ball 18 will engage the roller 34 at a different 50 point along the length thereof. Thus as seen in Fig. 1 the cap 22^a which co-operates with one of the lower ball contacts 18 is positioned some little outward or to the right of the cap 22^b which co-operates with one of the upper balls 18. It will be understood 55 that the particular relative endwise positioning of the several balls 18 is not material so long as each of them is mounted so as to engage the roll 34 at a different point along its length so that any particular portion of the length of said roll will only receive the wear from contact with one of the balls 18. Thus the durability of the contacts and 60 hence of the timer is greatly increased, it being of course understood that the several

balls 18 are constantly being shifted and turned so as to present fresh contact portions to the roll 34 while the roll 34 is also caused to turn at each contact so as to present a fresh peripheral portion at each contacting engagement with any given fixed contact, as well as presenting different endwise portions to the successive fixed contacts. It will also be noted that the roll 34 is a simple inexpensive element and easily removed for renewal or cleaning it having for 70 this purpose an endwise removable axis pin 34. For holding the sleeve 32 in place a nut 38 is threaded on the extremity of the shaft 30 to set up against said sleeve, this 80 nut being equipped with an outward cylindrical extension 39 which fits a bearing in the cylindrical extension 12 of the timer shell, said shell extension being also suitably equipped with an oil passage 40. By the 85 provision of this extension 39 it is insured that the timer shell 10 and the fixed contacts will be properly centered when the timer is applied to a driving shaft 30 pre-fixed in place as is the case with the cam shaft of a 90 Ford machine. I am aware that the invention can be embodied in other specific forms without departing from the essential attributes thereof and I therefore desire the present embodiment to be considered as 95 illustrative and not restrictive reference being had to the appended claims rather than to the foregoing description to indicate the scope of the invention.

Having described my invention, what I 100 claim as new and desire to secure by Letters Patent is:

1. A timer, comprising relatively fixed contacts spaced apart circumferentially and also along the axis of the timer, and a revoluble contact to co-operate therewith having a shaft mounting, said revoluble contact consisting in a shiftable member extending in the same general direction as the shaft and of a length sufficient to engage all of 110 said fixed contacts as it revolves.

2. A timer, comprising relatively fixed contacts spaced apart circumferentially and also endwise of the timer, and a revoluble contact to co-operate therewith having a 115 shaft mounting, said revoluble contact consisting in a roller fitted to turn on an axis extending in the same general direction as said shaft and of a length to engage all of said fixed contacts whereby it is turned 120 at each engagement with a fixed contact to present a fresh contact portion.

3. A timer, comprising a housing bearing a series of spaced apart fixed contacts and formed with a reduced bearing extension at 125 the outer end thereof, a shaft extending into said housing bearing a movable contact, and a nut engaging the end of said shaft to hold said movable contact in place, said nut having an extending cylindrical portion fitting 130

said bearing extension in said housing to hold said housing centrally alined with respect to said shaft.

4. A timer, comprising a housing formed of fiber or the like bearing a relatively fixed contact and having a projecting arm formed therewith, a metallic reinforce strip embedded in said arm with end portions ex-

tending therealong, and an intermediate portion formed to constitute a bearing for 10 an operating device engageable with said arm to shift the housing angularly.

In testimony whereof I have signed my name to this specification.

FREDERICK C. HERSEE.
